(57) CLAIM

The ornamental design for a ceiling panel, as shown and described.

DESCRIPTION

FIG. 1 is a perspective view of a ceiling panel, with its perimeter generally horizontally oriented and its main area projecting upwardly, showing my new design;

FIG. 2 is a perspective view thereof with its perimeter generally vertically oriented and its main area projecting into the foreground;

FIG. 3 is a perspective view thereof with its perimeter generally horizontally oriented and its main area projecting downwardly;

FIG. 4 is a perspective view thereof with its perimeter generally vertically oriented and its main area projecting into the background;

FIG. 5 is a top view thereof;

FIG. 6 is an edge view thereof;

FIG. 7 is a view of an edge thereof adjacent the edge of FIG. 6;

FIG. 8 is a view of an edge thereof opposite the edge of FIG. 6;

FIG. 9 is a view of an edge thereof opposite the edge of FIG. 7;

FIG. 10 is a bottom view thereof;

FIG. 11 is a view thereof, similar to FIG. 5, the broken line showing, looking upwardly, of a suspended ceiling grid and additional like ceiling panels, is for the purpose of illustrating the environment and the grid forms no part of the claimed design; and,

FIG. 12 is a view thereof, similar to FIG. 10, the broken line showing, looking down, of a suspended ceiling grid and additional like ceiling panels, is for the purpose of illustrating the environment and the grid forms no part of the claimed design.
